TOY VEHICLE WITH SIMULATED HORN

Harmer L. Cox, West Englewood, N. J., assignor
to Louis Marx & Company, New York, N. Y.,
a corporation of New York

Application July 13, 1948, Serial No. 38,442

10 Claims. (Cl. 46—111)

1

This invention relates to toys, and more particularly to vehicle toys such as toy autos.

The primary object of the invention is to generally improve toys of the specified character by equipping the same with a noise producing device simulating a warning signal or horn. Other objects are to provide a noise producing device which is simple in construction and inexpensive to manufacture, which is mechanically operated in order to avoid the need for batteries or the like, and which will operate in a dependable and trouble-free manner over a long span of life.

A more particular object is to provide a vehicle toy with a simulated steering wheel and steering column assembly at least a part of which is axially movable, and the movement of which may be used to operate the aforesaid noise producing mechanism. Still another object is to arrange the vehicle toy for steering, if desired, in which case the aforesaid simulated steering wheel and column assembly is suitably linked to the wheels so that rotation of the steering wheel turns the vehicle, while axial movement operates the noise producing mechanism or horn.

In accordance with a still further feature and object of the invention, the steering wheel and column assembly may include a rod the rear end of which projects through the center of the steering wheel, somewhat in simulation of an automobile horn button. In that species of the invention, rotation of the wheel steers the vehicle, and depression of the simulated button sounds the warning signal.

To accomplish the foregoing general objects, and other more specific objects which will hereinafter appear, my invention resides in the toy vehicle steering and noise making elements and their relation one to the other as are hereinafter more particularly described in the following specification. The specification is accompanied by a drawing in which:

Fig. 1 is a side elevation of a toy vehicle embodying some features of the present invention;

Fig. 2 is a fragmentary section taken approximately on the sloping line 2—2 of Fig. 1;

Fig. 3 is a vertical section taken approximately in the plane of the line 3—3 of Fig. 2;

Fig. 4 is a longitudinal section taken in elevation through the forward half of a modified form of the toy, in which the steering and warning operations are completely separated;

Fig. 5 is a horizontal section taken approximately in the plane of the line 5—5 of Fig. 4; and

2

Fig. 6 is a longitudinal section taken in elevation, generally similar to Fig. 4, but showing still another form of the invention in which the toy may be steered.

Referring to the drawing, all forms of the toy shown comprise a vehicle body B, a simulated steering wheel and column assembly generally designated A, at least a part of which is axially movable, resilient means R normally urging said part upwardly or rearwardly, a part having transverse serrations or threads T; and a leaf spring S arranged in cantilever and having its free end in rubbing engagement with the serrations or threads T. The toy further comprises means whereby depression of the axially movable part of the assembly A causes a relative rubbing movement of the spring S and the serrations T, thus producing a raucous noise in simulation of an automobile horn.

Considering the first species of the invention in greater detail, and referring to Figs. 1, 2 and 3 of the drawing, the toy there shown simulates a "jeep." There is a sheet metal body 12 supported on four wheels 14 and carrying a fifth wheel or spare 16. A simulated hood 18 may be raised about eyelets 20. A simulated windshield 22 may be raised about eyelets 24. The rather simple form of toy here shown is not arranged for steering, and is not provided with a propulsion motor. It is a so-called "pull" toy, which is simply pulled or pushed along by a child playing with the same.

The simulated steering wheel and column assembly A is shown in greater detail in Figs. 2 and 3 of the drawing. The steering wheel 26 is fixedly secured at the upper or rear end of a solid rod 28. The lower end of the rod is of reduced diameter, as indicated at 30. An intermediate portion 32 is threaded. The large diameter portion 28 is axially slidable and rotatable in a bearing 34. The small diameter portion 30 is axially slidable and rotatable in a bearing 36. The rod and wheel are normally urged rearwardly by a compression spring 38 coiled about the small diameter portion of the rod and disposed between bearing 36 and the threaded portion 32. The rearward movement of the rod is limited by suitable means, such as a split collar 40 fitted into a groove in the rod.

The leaf spring S is bent substantially at right angles. One end 42 is free for vibration and is in rubbing engagement with the thread 32. The opposite end 44 is fixedly mounted on a stationary wall 46, as by means of a rivet or eyelet 48. A lug 50 may be struck upwardly from wall 46

for engagement with the stationary end of the spring in order to prevent rotation of the spring about the eyelet 48. In this way one eyelet is sufficient to hold the spring in desired position.

The bearing wall 36 may be folded upwardly from the bottom wall 52 of the toy. The bearing wall 34 may be formed integrally with side walls 54, which in turn may be secured to bearing wall 36 by appropriate tongue and slot connections. The wall 46 may be formed integrally with one of the side walls, and whether integral or separate, may be locked in position by suitable tongue and slot connections, as is well understood by those skilled in the toy art.

It will be evident that the wheel 26 may be either rotated or depressed. When depressed and released, a relatively loud, raucous sound is produced by the movement in both directions, in simulation of an automobile horn or so-called "klaxon." The thread does not act as a thread, but rather as transverse serrations. A thread is simply one convenient way to provide the desired transverse serrations. Serrations along a square or flattened rod may be used, but the present arrangement not only facilitates rotation of the steering wheel, but has the incidental advantage of presenting an ever-changing surface to the spring, thus distributing the wear and increasing the life of the toy.

Another form of the invention is illustrated in Figs. 4 and 5 of the drawing. In this case the toy vehicle simulates a racing car. Only the forward end of the toy is shown, it being understood that the remainder of the toy, if shown, would include the usual cockpit and streamlined rear end with rear wheels. The toy may be either a pull toy, or a motor driven toy, and in the latter case, suitable clockwork mechanism housed in the rear portion of the toy is geared to the rear axle and wheels.

The front wheels 60 are mounted for steering. In the present case, stub axles 62 (Fig. 5) are carried by brackets 64 pivoted on simulated kingpins 66. The brackets have rearwardly extending arms 68 joined by a cross-link 70. In the arrangement here shown this link is stamped out of sheet metal and is generally T-shaped, with a rearwardly extending stem portion 72, the rear end of which is turned upwardly at 74, and slotted to receive the pin 76 of an oscillatable arm 78.

The steering wheel 80 (Fig. 4) is secured to a tube 82 rotatable in bearing walls 84 and 86. The tube 82 is held against axial movement, as by means of spring collars 88 fitted into mating grooves. The arm 78 is secured to the tube 82 in any desired manner. In the present case, the arm 78 is a piece of stiff, heavy gauge wire which is bent tightly about the tube, and additionally held, as by means of soldering, spot welding or the like. It will be evident from inspection of the drawing that rotation of the steering wheel 80 turns the tube 82 and arm 78, with consequent side to side movement of the pin 76 and with it the arm 72 and link 70. This turns or steers the front wheels about the kingpins 66.

A rod 90 is axially movable in tube 82. The rear end 92 of the rod projects through the middle of the steering wheel, somewhat in simulation of a horn button. The lower end of the rod projects beyond the tube 82. An intermediate portion 94 is threaded, while the lowermost portion 96 is preferably smooth and slidably received in a bearing wall 98. A compression spring 100 is

coiled about the rod and disposed between the wall 98 and a suitable collar 102. Thus the rod is normally urged rearwardly, its movement being limited by means of a spring collar 104. In the alternative, the collar 102 may be permitted to reach the spring S.

The leaf spring S may be similar to that previously described, it having a free end bearing against the serrations or threads 94, while the opposite end portion 106 is fixedly secured to the vehicle body, as by means of an eyelet 108. This anchors the spring on a wall 110 which may be formed integrally with or otherwise secured to the bearing walls 86 and 98 previously referred to, which in turn may be mounted in the vehicle body by means of suitable tongue and slot connections.

It will be evident that depression of the simulated horn button 92 will produce the desired signal noise, and that the control elements for the warning signal and for steering are separated from one another in better simulation of a real automobile. However, the steering column assembly resembles the others in having a part which is axially movable for noise making purposes.

It is not essential to separate the control elements in order to steer the vehicle. Fig. 6 illustrates a modified toy arranged to both steer and 30 to produce a warning signal, but in which the wheel is axially movable. Considering the arrangement in detail, the front wheels 112 are steerable and may be mounted on kingpins as previously described, and may be operated by 35 linkage similar to that previously described, except that in the present case the rearwardly extending stem portion 114 of the T-shaped link 116 may be shorter. It is similarly provided with an upturned end 118 slotted to receive the pin 120 of an arm 122 secured to rod 124. However, in the present case the pin 120 is lengthened to 40 accommodate axial movement of the rod without in any way affecting the steering of the vehicle.

The steering wheel 126 is fixedly secured on 45 the rear end of a steering rod 128, which in the present case may be a simple solid rod. The rod is both slideable and rotatable in a bearing wall 130. An intermediate portion of the rod is serrated or threaded, as indicated at 132. The lower end portion 124 of the rod is rotatable and 50 slideable in a bearing bracket 134 mounted on the vehicle body at 136. A spring 138 is coiled about the rod 124 and is disposed between the bearing 55 134 and the arm 122. Thus the rod is normally urged rearwardly. The leaf spring S may be similar to those previously described, it having a free end 140 in rubbing contact with the thread 132. The opposite end 142 is fixedly mounted on a forwardly extending mounting lug 144, as by 60 means of a rivet or eyelet 146. As before, a single eyelet may be employed if the spring is so dimensioned that parts of the spring bear against parts of the vehicle in such a manner as to prevent rotation of the spring about the eyelet.

It will be understood that with this arrangement depression or axial movement of the steering wheel produces the desired warning signal, while rotation of the steering wheel, whether in rearward, forward or intermediate position, effectively turns the front wheels and consequently 70 steers the vehicle. Pin 120 is preferably parallel to rod 128.

It is believed that the construction and operation of my improved toy, as well as the advantages thereof, will be apparent from the foregoing.

ing detailed description. The noise making device or warning signal is simple, inexpensive and dependable in operation. It is combined with the steering wheel and steering column assembly in a manner which adds to the realism of the toy. The toy may be arranged to steer under control of the steering wheel, independently of the operation of the warning signal.

While the illustrated toys employ a single leaf spring, toys of my invention have been made with a pair of oppositely directed leaf springs, the inner or free ends of both springs bearing on the threaded rod on opposite sides thereof. Transverse serrations may be used in lieu of a continuous thread. In fact, in some forms of the invention, the serrations may be formed on a flat surface instead of entirely around a rod, but the latter is convenient and advantageous.

It will therefore be apparent that while I have shown and described my invention in several preferred forms, changes may be made in the structures shown, without departing from the spirit of the invention as sought to be defined in the following claims.

I claim:

1. A toy vehicle having a vehicle body and a noise making mechanism for simulating the horn of an auto, said toy vehicle comprising a simulated steering wheel and column assembly including a round rod, bearings in said vehicle body slidably supporting said round rod for movement in axial direction along the axis of the rod, a part of said rod housed by said body being spirally threaded, and a leaf spring mounted on said body at one end and disposed transversely of the rod, the other end of said spring being free and in rubbing contact with the aforesaid threads on the rod, said mounted end being secured fixedly to said vehicle body.

2. A wheeled vehicle toy comprising a vehicle body, and noise making mechanism including a simulated steering wheel and column assembly at least a part of which assembly is movable in the direction of the axis of the column, resilient means normally urging said part rearwardly, an element having serrations which are transverse relative to the axis of the column, a leaf spring mounted at one end and free at its other end and having its free end in rubbing engagement with said serrations, and means whereby movement of the axially movable part of the aforesaid steering wheel and column assembly causes a relative movement of the serrated element and the leaf spring.

3. A toy vehicle as defined in claim 2, in which the steering wheel and column assembly comprises a rod mounted for both rotation about the axis of the rod and axial movement along the axis of the rod, the steering wheel being secured to the rear end of said rod, and the aforesaid resilient means normally urging said rod and steering wheel rearwardly, whereby a noise is produced by depressing the steering wheel and rod forwardly.

4. A toy vehicle as defined in claim 2, in which one or more wheels are mounted for steering, and in which the steering wheel and column assembly comprises a tube mounted for rotation about the axis of the tube but held against axial movement along the axis of the tube, said steering wheel being secured to the rear end of said tube, and a rod mounted within said tube for movement along the axis of the rod and tube, the forward end of said rod extending beyond said tube, the aforesaid resilient means normally urging

5 said rod rearwardly, said rod carrying the aforesaid serrations, the rear end of said rod projecting through the center of the steering wheel in simulation of an automobile horn button, and steering linkage between the steerable wheels and the rotatable tube.

10 5. A toy vehicle as defined in claim 2, in which one or more wheels are arranged for steering, and in which the simulated steering wheel and 15 column assembly comprises a rod mounted for both axial movement along and rotation about the axis of the rod, the steering wheel being secured to the rear end of said rod, the aforesaid resilient means urging said rod and wheel rearwardly, and steering linkage between said steerable wheels and said rod, said linkage including a connection such as to accommodate the aforesaid axial movement of the rod without affecting the steering resulting from rotation of said rod.

20 6. A wheeled vehicle toy comprising a vehicle body, and noise making mechanism including a simulated steering wheel and column assembly at least a part of which assembly is movable in 25 the direction of the axis of the column, resilient means normally urging said part rearwardly, said part having transverse serrations, and a leaf spring mounted at one end on said vehicle and free at its other end and disposed transversely of said part and having its free end in rubbing engagement with said serrations.

30 35 7. A toy vehicle as defined in claim 6, in which the steering wheel and column assembly comprises a rod mounted for both rotation about the axis of the rod and axial movement along the axis of the rod, the steering wheel being secured to the rear end of said rod, and the aforesaid resilient means normally urging said rod and steering wheel rearwardly, whereby the desired 40 signal noise is produced by depressing the steering wheel and rod forwardly.

45 8. A toy vehicle as defined in claim 6, in which there are front wheels mounted for steering, and in which the steering wheel and column assembly 50 comprises a tube mounted for rotation about the axis of the tube but held against axial movement along the axis of the tube, said steering wheel being secured to the rear end of said tube, and a rod mounted within said tube for movement 55 along the axis of the rod and tube, the forward end of said rod extending beyond said tube, the aforesaid resilient means normally urging said rod rearwardly, said rod carrying the thread, the rear end of said rod projecting through the center of the steering wheel in simulation of an automobile horn button, and steering linkage between the steerable front wheels and the rotatable tube, whereby rotation of the steering wheel steers the toy, and depression of the simulated 60 horn button produces the desired noise.

65 9. A toy vehicle as defined in claim 6, in which the vehicle has front wheels which are arranged for steering, and in which the simulated steering wheel and column assembly comprises a rod mounted for both axial movement along and rotation about the axis of the rod, the steering wheel being secured to the rear end of said rod, the aforesaid resilient means urging said rod and wheel rearwardly, and steering linkage between 70 said steerable front wheels and said rod, said linkage including a slid able connection such as to accommodate the aforesaid axial movement of the rod without affecting the steering resulting from rotation of said rod, whereby rotation

of the steering wheel steers the vehicle, and depression of the steering wheel produces a noise.

10. A wheeled toy auto comprising a vehicle body, and noise making mechanism including a simulated steering wheel and column assembly at least a part of which assembly is movable in the direction of the axis of the column, a compression spring normally urging said part rearwardly, said part being threaded, and a leaf spring arranged transversely of said part and having one end in rubbing engagement with said thread, the other or stationary end of said leaf spring being fixedly secured to a part of the vehicle body.
